UNITED STATES PATENT OFFICE

EDWIN ARCHER TURNER, OF NEW YORK, N. Y., ASSIGNOR TO THE STANDARD STOKER COMPANY, INCORPORATED, A CORPORATION OF DELAWARE

STOKER CONVEYER

Application filed September 15, 1930. Serial No. 431,834.

This invention relates to conveying mechanism and more particularly to fuel conveying mechanism for a locomotive stoker.

One of the objects of the invention is the provision in a locomotive stoker of new and improved means for conducting the fuel in a direct course from the tender to the firing opening in the backhead of the locomotive.

A further object of the invention is to simplify, lighten and improve the efficiency of transferring mechanism for moving fuel from the fuel bin of a locomotive tender to a point of discharge into the firebox of the locomotive.

Other and further objects and advantages will appear from the following description taken in connection with the accompanying drawings, in which

Fig. 1 is a longitudinal vertical section of a portion of the locomotive and tender, showing the invention in position thereon;

Fig. 2 is a plan view thereof, with parts broken away, parts in section; and

Fig. 3 is a longitudinal, vertical section similar to Fig. 1 showing a modified form of the invention in place on the locomotive and tender.

Referring now to the drawings, the reference character 10 designates a locomotive having a firebox 11 provided in its rear wall with a hand firing opening 12 which may be and preferably is the usual hand firing opening. The locomotive 10 is provided with the usual deck 13, and the tender shown at 15 is provided with a floor 14 having a fuel opening 16 therethrough, through which fuel is supplied by gravity to the trough portion 17 of the transfer conduit 18 as is usual in such constructions. Plates 16a are slidably mounted in the opening in a manner well known in the art.

The transfer conduit 18 comprises the trough portion 17 and the tubular extension 19 leading forwardly from the trough portion 17 and then bent upwardly extending toward the firing opening. The transfer conduit 18 is formed of a single casting thereby eliminating a joint at the bend in the conduit providing a rigid, durable, simple and economical construction. A suitable

sectional conveyer screw 20 comprising the sections 21 and 22 is rotatably mounted in the conduit 18, and a universal joint 23 connects the screw sections 21 and 22 adjacent the bend in the conduit.

The transfer conduit 18 is supported beneath the opening 16 by rollers 24 on the rails 25 whereby the conduit may move longitudinally of the rails and may have a slight angular movement to provide for articulation between the locomotive and tender. The conduit 18 is flexibly connected to and supported at its forward end by the mouth member 26 as will presently appear.

The mouth member 26 is rigidly attached to the backhead of the locomotive by suitable means, such as the bolts 27, and communicates at its forward end with the firing opening 12. In the preferred embodiment of the invention as shown in Figs. 1 and 2, the mouth member 26 extends rearwardly and

downwardly terminating beneath the cab deck 13 in a vertically split flange 28 arranged to receive the ball member 29 of the conduit 18 thereby affording universal movement between the conduit 18 and mouth member 26. In this preferred construction no movable parts extend above the cab deck.

Suitable means is provided for operating the sectional screw conveyer 20. A motor 29 is mounted on the tender and operates the sectional screw conveyer 20 from the rear end thereof by the angularly arranged power shaft 30 through the spur gears 31 and 32, see Fig. 2. The power shaft 30 is provided with universal joints 33 and 34 at its end portions for accommodating its angular position relative to the motor and the gears.

The mouth member 26 discharges upon a distributor plate 35 which projects through the firing opening 12 and is provided at its rearward end with a distributor head 36 having jet openings 37 arranged to discharge a blast of pressure fluid over the face of the plate whereby fuel delivered to the plate is scattered into the firebox in aerial paths.

Figure 3 shows a modification in which the tubular extension 19 of the transfer conduit 18 extends above the cab deck, and is univer-

sally jointed at a point above the cab deck to two screw sections being universally connected at the juncture of the rearward and forward portions of the transfer conduit.

In operation, fuel passes by gravity through the opening 16 in the floor 14 of the tender into the trough portion 17 of the transfer conduit 18. The sectional screw conveyer moves the same along the bottom of the conduit past the crusher 38, which reduces the oversize lumps, and urges it through the mouth member 26 onto the distributor plate 35 where it is projected into the firebox by steam or other fluid under pressure from the distributor head 36.

It will be apparent that I have provided a novel conveying system that is cheap to manufacture, simple in construction, having a minimum number of parts and that is efficient in operation.

I claim:

20 1. In combination, a locomotive provided with fire-box having a backwall with a firing opening therein, a tender, a fuel conveying system comprising a tubular conduit fixed rigidly to said backwall and communicating with said firing opening, a unitary transfer conduit composed of a rearward substantially horizontally disposed portion movably mounted on the tender and an upwardly inclined forward portion at its forward end flexibly attached to and in end to end relation with the rearward end of said tubular conduit, and a sectional screw in said transfer conduit comprising the sole fuel advancing means in said fuel conveying system

25 comprising a screw section in said rearward portion and a screw section in said forward portion, the latter section terminating adjacent the rearward end of said tubular conduit and the two screw sections being universally connected at the juncture of the rearward and forward portions of the transfer conduit.

2. In combination, a locomotive provided with a fire-box having a backwall with a firing opening therein, a cab and deck therefor, a tender, a fuel conveying system comprising a tubular conduit fixed rigidly to said backwall and communicating with said firing opening, the aforesaid conduit extending rearward and downward from said opening to a point beneath said deck, a unitary transfer conduit composed of a rearward substantially horizontally disposed portion movably mounted on the tender and an upwardly inclined forward portion at its forward end flexibly attached to and in end to end relation with the rearward end of said tubular conduit, and a sectional screw in said transfer conduit comprising the sole fuel advancing means in said fuel conveying system comprising a screw section in said rearward portion and a screw section in said forward portion, the latter section terminating adjacent the rearward end of said tubular conduit and the

In testimony whereof I affix my signature.

E. ARCHER TURNER.

DISCLAIMER

1,814,648.—*Edwin Archer Turner*, New York, N. Y. STOKER CONVEYER. Patent dated July 14, 1931. Disclaimer filed January 27, 1932, by the assignee, *The Standard Stoker Company, Inc.*

Hereby enters this disclaimer to that part of the claim in said specification which is in the following words, to wit:

“1. In combination, a locomotive provided with fire-box having a backwall with a firing opening therein, a tender, a fuel conveying system comprising a tubular conduit fixed rigidly to said backwall and communicating with said firing opening, a unitary transfer conduit composed of a rearward substantially horizontally disposed portion movably mounted on the tender and an upwardly inclined forward portion at its forward end flexibly attached to and in end to end relation with the rearward end of said tubular conduit, and a sectional screw in said transfer conduit comprising the sole fuel advancing means in said fuel conveying system comprising a screw section in said rearward portion and a screw section in said forward portion, the latter section terminating adjacent the rearward end of said tubular conduit and the two screw sections being universally connected at the juncture of the rearward and forward portions of the transfer conduit.”
